UNITED STATES PATENT OFFICE.

JOHN ZELINSKY, OF PORTSMOUTH, VIRGINIA.

RAIL JOINT.

1,425,736.

Specification of Letters Patent. Patented Aug. 15, 1922.

Application filed February 1, 1922. Serial No. 533,170.

To all whom it may concern:

Be it known that I, JOHN ZELINSKY, citizen of Czechoslovakia, residing at Portsmouth, in the county of Norfolk and State of Virginia, have invented certain new and useful Improvements in Rail Joints, of which the following is a specification.

This invention relates to rail joints for railroad tracks, and it has for an object to 10 provide a simple and efficient joining means for securely holding the rail ends against displacement.

For further comprehension of the invention, and of the objects and advantages 15 thereof, reference will be had to the following description and accompanying drawings, and to the appended claims in which the various novel features of the invention are more particularly set forth.

20 Fig. 1 of the drawings is a detail perspective view showing a pair of rail ends with my improved joint applied thereto.

Fig. 2 is a side view thereof, one of the fish plate members being omitted.

25 Fig. 3 is a transverse section on the line 3—3 of Fig. 2.

Fig. 4 is a transverse section on the line 4—4 of Fig. 2.

In the drawings the reference numeral 10 30 designates a pair of rail ends of ordinary construction. My improved rail joint comprises a chair member having a bottom plate 11 which extends under the base-flanges of the rail ends and on which the latter rest.

35 Formed integral with the plate 11 at one edge thereof is a fish-plate member which presents a lower inclined portion 12 fitting snugly over the base-flanges of the rail ends on one side thereof, and a vertical portion 13 fitting against the vertical flange of the rail. The bottom plate 11 may be reinforced by a longitudinal rib 13 formed on the underside thereof.

40 Formed integral with this chair element midway between opposite ends thereof is a thin transverse web 15 which fits between the rail ends, having an upper portion 16 which corresponds in transverse outline to the tread of the rail and is flush at its top therewith, this web projecting at its side laterally beyond the rail web forming an outstanding ear or lug.

45 Fitting snugly against the opposite side of the rail to that engaged by the member 13 are a pair of fish-plate members 18 having inclined foot-flanges 19 resting on the base-

flange of the rail. These fish-plate members 18 abut at their adjacent ends against opposite sides of the ear 15 and are formed at said ends with transverse walls 20, engaging 60 said ear on opposite faces thereof and secured thereto by bolts 21 passing through suitable registering openings in said parts and having nuts 22 threaded on their ends, these walls 20 being flush at the top and 65 side with the ears 15.

The foot-flanges 19 and chair-plate element 11 are bound to the rail by means of channeled clips 25 which engage over said foot-flanges and under said chair plate element. These clips 25 are secured in place by means of rectangular bolts such as 26 having each a hooked end 27 engaging over the inclined chair plate element 12, these bolts being passed through suitable channels 75 such as 28 in the bottom chair plate element 11 and having diminished cylindrical ends 29 inserted through suitable apertures in the clips 25 and suitably screw threaded to receive fastening nuts 30 which bear against 80 the clips. As an additional fastening means bolts 32 may be passed through suitable registering apertures in the members 11 and 19 and the base-flange of the rail.

As will be apparent, I have provided a 85 rail joining means characterized by great strength and rigidity, the elements on opposite sides of the rail having a direct union with one another by means of the transverse web 15.

Having thus described my invention what I claim as new and desire to protect by Letters Patent of the United States is as follows:

1. In combination with a pair of rail ends, 95 a chair-plate element presenting between its ends a transverse ear fitting between the rail ends, and a pair of fish-plate elements abutting against said ear, said fish-plate elements having at their adjacent ends transverse 100 webs engaging said ear on opposite sides thereof.

2. In combination with a pair of rail ends, 105 a chair-plate element presenting between its ends a transverse ear fitting between the rail ends, and a pair of fish-plate elements abutting against said ear, said fish-plate elements having at their adjacent ends transverse webs engaging said ear on opposite sides thereof, and fastening bolts passed through 110 said ear and webs.

3. In combination with a pair of rail ends,

a chair member having a bottom plate engaging under the rail ends, a fish-plate element having a foot flange resting on the base flange of the rail, a pair of channeled clips straddling said foot flange and bottom plate, and a pair of fastening bolts passed through transverse channels in said bottom plate and through apertures in said clips.

4. In combination with a pair of rail ends, 10 a chair member having a bottom plate engaging under the rail ends, a fish-plate ele-

ment having a foot flange resting on the base flange of the rail, a pair of channeled clips straddling said foot flange and bottom plate, and a pair of fastening bolts passed 15 through transverse channels in said bottom plate, and through apertures in said clips, said bolts having integral hooked ends engaging said chair-plate element.

In testimony whereof I have affixed my 20 signature.

JOHN ZELINSKY.
